ABSTRACT

A container and dispenser for a plurality of rolls of tissue paper comprises a substantially L-shaped container having a substantially vertical part adapted to be mounted on a wall and having a substantially horizontal cover hingedly affixed to the top thereof. A substantially horizontal part extends at substantially right angles with the vertical part at the bottom thereof and has a common bottom with the vertical part. The horizontal part has an open top in a substantially horizontal plane whereby a plurality of rolls of tissue paper stored in the vertical part moves the lowermost roll into the horizontal part into accessibility at the open top thereof.

FIG.1

FIG.2

FIG.3

FIG.4

**TISSUE PAPER ROLL CONTAINER AND
DISPENSER**

DESCRIPTION OF THE INVENTION:

The present invention relates to a tissue paper roll container and dispenser. More particularly, the invention relates to a container and dispenser for a plurality of rolls of tissue paper.

The principal object of the invention is to provide a tissue paper roll container and dispenser of simple structure for handily and conveniently storing a plurality of rolls of tissue paper and making the rolls available with facility, convenience, conform and rapidity.

In order that the invention may be readily carried into effect, it will now be described with reference to the accompanying drawing, wherein:

FIG. 1 is a schematic diagram of an embodiment of the container and dispenser of the invention;

FIG. 2 is a sectional view of the embodiment of FIG. 1;

FIG. 3 is a front view of the embodiment of FIG. 1; and

FIG. 4 is a back view of the embodiment of FIG. 1.

In the FIGS., the same components are identified by the same reference numerals.

The container and dispenser of the invention is for a plurality of rolls of tissue paper. The container and dispenser of the invention comprises a substantially L-shaped container having a substantially vertical part 1 (FIGS. 1, 2, 3 and 4). The vertical part 1 has a pair of apertures 2 and 3 (FIG. 4) formed through its back 4 (FIG. 2) so that it may readily be mounted on a wall.

A substantially horizontal cover 5 is hingedly affixed to the top 6 of the vertical part 1 (FIGS. 1, 2 and 3).

A substantially horizontal part 7 (FIGS. 1, 2 and 3) extends at substantially right angles with the vertical part 1 at the bottom 8 thereof (FIGS. 1, 2 and 4). The horizontal part 7 has an open top 9 (FIGS. 1, 2 and 3) in a substantially horizontal plane.

Thus, a plurality of rolls of tissue paper 10, 11, 12 and 13 (FIG. 2) stored in the vertical part 1 moves the lowermost roll 13 into the horizontal part 7 into accessibility at the open top 9 thereof.

One or more windows 14 and 15 of any desirable configuration (FIGS. 1 and 3) are formed through the vertical part 1 to permit visual inspection of the contents of said vertical part.

I claim:

1. A container and dispenser for a plurality of rolls of tissue paper, and container and dispenser comprising a substantially L-shaped container having a substantially vertical part adapted to be mounted on a wall and having a substantially horizontal cover hingedly affixed to the top thereof and a substantially horizontal part extending at substantially right angles with the vertical part at the bottom thereof and having a common bottom with the vertical part, the horizontal part having an open top in a substantially horizontal plane whereby a plurality of rolls of tissue paper stored in the vertical part moves the lowermost roll into the horizontal part into accessibility at the open top thereof.

2. A container and dispenser as claimed in claim 1, wherein the vertical part has a window formed therethrough to permit visual inspection of the contents of the vertical part.
